UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

METHOD OF SPLICING TOGETHER WARP THREADS.

Refiled for abandoned application Serial No. 6,911, filed February 8, 1915. This application filed December 20, 1921. Serial No. 523,766.

To all whom it may concern:

Be it known that I, EDGAR F. HATHAWAY, a citizen of the United States, and resident of Wellesley, in the county of Norfolk and

5 State of Massachusetts, have invented certain new and useful Improvements in Methods of Splicing Together Warp Threads, of which the following is a specification.

10 This invention comprises a novel method of securing together or splicing the ends of the threads of two sets of warps in order to enable one set already in the harness of the loom to draw in after it the other set of 15 warps.

In carpet looms and some other looms for weaving pile fabrics, it has been the practice when the last ends of the warp threads are reached to tie to those ends the

20 corresponding ends of a full warp beam in order that the old threads might be drawn through the harness eyes by the tail ends of the warp threads already located in the loom harness. This method of knotting to-

25 gether the two sets of warp threads not only consumes a great deal of the time of the operator but in cases where, as in carpet weaving, each warp element consists of a bundle of tuft or thick threads arranged

30 together to form a single warp, the knot is naturally large and cumbersome and likely to cause trouble when the attempt is made to draw the knot through the eye in the harness. Furthermore, there is also liability to error through carelessness or inatten-

35 tion in tying together long ends of the two sets of warps that do not correspond.

To overcome these difficulties, I have devised a method by which the ends of the 40 nearly exhausted warp may be effectively and quickly secured to the ends of the succeeding warp beam without forming objectionable knots in the warps, while also avoiding loss of time and liability to error 45 in tying together the wrong threads of the two sets of warps.

The following specification describes the 50 method of procedure comprising my invention, and it will be understood that this method may be carried out by hand while also lending itself to more expeditious results by the use of any suitably designed

automatic or partly automatic machine that may be devised for this purpose.

In the accompanying drawings, I have 55 illustrated various steps in the practice of my improved method of splicing together the ends of the respective warp threads, but it will be understood that the particular form of implement shown, as well as the 60 particular form of the clips used, are merely illustrative, and that the invention is not confined to any special form of accessory devices.

Figure 1 represents a perspective of the 65 two warp ends secured in spacing clamps preparatory to bringing them into over-lapped relationship to the guide or spacer.

Figure 2 is a similar view showing the 70 one set of warp threads laid across the guide.

Figure 3 shows the two sets of warp threads over-lapped and with each corresponding pair of warp ends united together.

Figure 4 is a detail view showing a 75 convenient form of clip.

Figure 5 is a perspective showing in detail a pair of over-lapped warp ends fastened together.

Before the splicing operation is begun, 80 each set of warp threads is secured by a spacing clamp of convenient form which, as shown in Figure 1, embraces a comb-like spacing bar *a* with a cooperating cover or clamp member *b* of trough-like or U-shaped 85 cross section adapted to be forced down over the ends of the comb teeth *a'* between which are laid in regular succession the warp ends *c* of one set of warps. The other set of warp threads are held in the same relationship that they occupy on the beam by means of the similar spacing clamp *ab*.

The first step in the operation after the warp threads have been clamped and spaced in their predetermined order is to bring the 90 two sets of warps together with the corresponding threads of one warp over-lapping the corresponding threads of the other warp. The certainty and quickness of this operation is facilitated by the use of a simple guide member *e* provided with guide teeth *e'* arranged to be easily inserted between the individual threads of each warp or, what amounts to the same thing, one en-

tire set of warp threads may at a single operation by means of its spacing clamp be laid into the appropriate spaces between the guide teeth e' . When this is done, the other 5 set of warp threads are similarly laid into the guide with each warp end superimposed above the corresponding warp end of the other set.

The two sets of warp threads being now 10 brought into juxtaposition in over-lapped relationship may be rapidly connected together in pairs by securing an individual fastening clip or member around each pair of over-lapped ends. The form of the clip 15 is unimportant. They may be made of spring material capable of being opened by the fingers in order to be passed around an over-lapped pair of warp ends, as indicated at f in Figure 5, the resiliency of the metal 20 serving to contract it upon the threads, or it may be in the form of a blank of soft metal or other suitable material which may be clamped or pinched around a pair of warp ends by means of the fingers of the 25 operator or by means of special pliers, or even, if desired, by a special machine designed for this purpose.

The clips or tie members will preferably be made of small dimensions so that when 30 pinched or pressed into the soft yarn they will afford no large obstruction to the easy passage of the spliced ends through the harness eyes.

It will be observed that the practice of 35 this process results in a new product or article of manufacture consisting of two series of parallel threads, the ends of one series being over-lapped on the corresponding ends of other series, each pair of over-

lapped ends being fastened together by an 40 external fastening clip, and this is a feature of the present invention.

What I claim is:

1. The herein described method of splicing together two sets of warp threads which 45 consists in positioning the ends of the threads of each set in a predetermined order properly spaced apart then bringing the two sets together with the ends of one set over-lapping the corresponding ends of the other 50 set, and then uniting the over-lapped pairs of ends by clinching around and upon each pair, an encircling fastening clip, substantially as described.

2. The herein described method of uniting two sets of warp threads which consists in first bringing together into uniformly spaced relationship the whole series of individual warp ends of the warp set and securing them in such relation, then bringing the respective ends into overlapped relationship with the corresponding ends of a similarly held and arranged set of warp threads by means of a common receiving and spacing element, and then clinching upon and 60 around each overlapped pair of thread ends, an encircling fastening strip, substantially as described.

3. The herein described article of manufacture comprising two series of warp 70 threads whose corresponding ends are overlapped upon each other, and a series of metallic fastening clips clinched around the respective pairs of over-lapped ends substantially as described.

It witness whereof, I have subscribed the above specification.

EDGAR F. HATHAWAY.
